ANTENNA REGULATOR

Filed Aug. 12, 1927

Inventor:
Joseph E. Love,
Alexander S. Hunt,
His Attorney.

UNITED STATES PATENT OFFICE

JOSEPH E. LOVE, OF SCHENECTADY, NEW YORK, ASSIGNOR TO GENERAL ELECTRIC COMPANY, A CORPORATION OF NEW YORK

ANTENNA REGULATOR

Application filed August 12, 1927. Serial No. 212,574.

My present invention relates to means for controlling the resonant wave length of an antenna system.

In my United States Patent No. 1,684,235 issued September 11, 1928, entitled "Automatic antenna regulator", and which is assigned to the same assignee as the present application, I have disclosed a system for the purpose indicated wherein the energization 10 of a magnetic amplifier which is associated with the antenna is controlled responsively to impedance variations in the antenna. To accomplish this the excitation of the generator which supplies control current to the 15 magnetic amplifier is varied by a vibratory member, the action of which is modified responsively to impedance variations in said antenna.

My present application, which is a continuation in part of my above-mentioned patent 20 has for its purpose to provide further means for automatically controlling the tuning of the antenna in response to changes of the antenna impedance.

25 While my above-mentioned patent discloses a very satisfactory means for accomplishing the desired result my present invention has for its purpose to provide means which may be more economically constructed 30 and which at the same time is sufficiently rapid in its operation to effect the desired adjustment of the antenna in response to sudden impedance changes such as occur during stormy weather conditions.

35 In carrying my present invention into effect I propose to control an antenna regulating means such as a variometer, which is usually employed in the antenna circuit, by mechanical means such as a clutch, or, in a 40 still more economical construction, by means of a motor, the operation of either of which may be electrically controlled in accordance with antenna impedance variations as indicated by the modified action of the vibratory 45 member of my former application. I further provide means whereby the mechanical means are rendered unresponsive to normal action of the vibratory member, or to impedance variations of the antenna resulting 50 from intentional detuning thereof, as, for

example, in cases where the keying operation is effected by detuning of the antenna.

The novel features which I believe to be characteristic of my invention will be set forth with particularity in the appended 55 claims. My invention itself, however, both as to its organization and method of operation will best be understood by reference to the following description taken in connection with the accompanying drawings, in 60 which Fig. 1 is a representation of one form of my invention; Fig. 2 shows a cross sectional view of a preferred form of clutch which I employ in connection therewith. The form of my invention shown in Fig. 1 and 65 Fig. 3 represents a modification.

Referring to the drawings I have indicated at 1 a well-known type of high frequency inductor alternator having a plurality of stationary armature windings 2 and 70 a rotary inductor 3, the latter being driven by a constant speed machine 4. Certain of the armature windings 2 are connected to the primary windings of a transformer 5, the secondary winding of which is connected in series relation with an antenna 6. Included in circuit with the antenna 6 are a variable impedance 7, which may comprise the impedance of a variometer such as is usually employed in systems of this kind, 75 and a pair of primary transformer windings 8 and 9 which are inductively related to a pair of secondary transformer windings 10 and 11.

For the purpose of interrupting in accordance with desired signals, the radiation of currents supplied to the antenna 6 from the alternator 1, a saturated core regulator or magnetic amplifier 12 is employed. This magnetic amplifier is of well-known construction and comprises a pair of high frequency windings 13 which are connected through condensers 14 and 15 to a coil 16 which is in inductive relation to a portion of the antenna circuit. If desired this coil 95 may constitute a third winding upon the transformer 5. A winding 18, in inductive relation with the windings 13 upon the magnetic amplifier, is supplied with direct current from a source 19 through a contact 100

making key 20 which may be operated in accordance with the desired signals. Thus when the key 20 is in the position shown in the drawing the circuit of the coil 18 is interrupted and the impedance of the amplifier 12 will be such that potential impressed upon the secondary winding of the transformer 5 from the alternator 1 will produce radiation from the antenna 6. When the key 20 is moved to the left into engagement with its left hand contact, current will flow in the winding 18, thereby so varying the impedance of the amplifier as to detune the antenna and thereby to prevent radiation therefrom.

For the purpose of regulating the impedance of the antenna the variometer 7 is provided with a shaft, which is represented by the dotted line 21 in the drawings and which is adapted to be rotated in one direction or the other by means of a clutch mechanism which is represented at 22. This mechanism comprises a pair of disks 23 and 24 which are adapted to be rotated in opposite directions by means of a continuously rotating motor 25 operated through a suitable gearing mechanism 26. The rotatable shaft 21 of the variometer 7 is extended through the centers of the disks 23 and 24 and has attached thereto a pair of disks 27 and 28 each of which are adapted to cooperate respectively with disks 23 and 24. Each of the disks 23 and 24, as is better shown in Fig. 2, is made integral with sleeves 29 and 30 respectively which are loosely mounted upon the shaft 21. These sleeves and the cooperating disks are made of magnetic material. Upon the sleeves are mounted coils 31 and 32 which are adapted to be energized in accordance with impedance variations of the antenna. The arrangement is such that if the coil 31 is energized the disk 27 will be actuated into frictional engagement with the disks 23 and the shaft 21 will be caused to rotate in a direction such that the inductance of the antenna will be, for example, increased by the variometer 7, whereas if the coil 32 becomes energized the disk 28 will be actuated into frictional engagement with the disk 24 and the shaft 21 will be rotated in a direction to decrease the inductance of the antenna. The motor 25 which maintains the disks 23 and 24 in continuous rotation is energized through conductors 33 and 34 from a source of potential 35. For the purpose of controlling the energization of the windings 31 and 32, relays 36 and 38 are provided, the details and operation of which will be presently set forth.

The relay 36 comprises a bent permanent magnet 36a carrying at one end a vibratory arm 39 which is adapted to cooperate with a pair of polarized members 40 and 41 of like polarity and a pair of contacts 42 and 43, the latter contacts being adapted to control

the operation of the relay 37. Polarized member 40 is mounted on a core member which carries a pair of windings, one of which 44 may be energized from a 60 cycle source of power indicated at 45, while the other winding 46 is included in circuit with an electron discharge device 47. Polarized member 41 is mounted on a core member which carries a pair of windings 48 and 49 similar to windings 44 and 46. Windings 44 and 48, however, are wound to produce opposite polarity with respect to one another. Winding 49 is connected in circuit with the second electron discharge device 50. The vibratory member 39 is connected through the contact of the relay 38 and the actuating winding of relay 37 to the neutral point between the source of potential 35 and 51. The relay 37 similarly with the relay 36 is of a polarized type its armature being adapted to engage contacts 52, or 53, depending upon the direction of the current flowing through its actuating winding. Thus, for example, if the vibratory member 39 of the relay 36 engages its contact 42 current will flow from the positive side of the source of potential 51 through the contact 42, vibratory member 39, contacts of the relay 38, actuating winding of the relay 37 back to the negative side of the source of potential 51. The relay 38 will thereby be energized in a manner to cause its armature to move into engagement with the contacts 53, thereby closing a circuit leading from the negative side of the source of potential 35 through the contacts 53 and armature of the relay 37, coil 32 of the magnetic clutch 22 and conductor 55 to the positive side of the source of potential 51 and thence back to the source of potential 35. Likewise if the vibratory member 39 engages its contact 43 a circuit will be closed from the negative side of the source of potential 35 through the contacts 43 and member 39, contacts of the relay 38 and actuating coil of the relay 37 to the positive side of the source of potential 35. Relay 37 will then actuate its armature into engagement with contacts 52, thereby closing a circuit leading from the negative side of the source of potential 35 through the contacts 52 and armature of the relay 37, coil 31 of the magnetic clutch 22 and conductor 55 to the positive side of the source of potential 51.

When 60 cycle current is supplied to the coils 44 and 48 of the relay 36 the member 39 will be caused to vibrate at 60 cycles remaining in engagement with the contacts 42 and 43 alternately for an equal period of time, thereby alternately energizing the winding of the relay 37 with currents of opposite polarity. The armature of the relay 37, however, is provided with sufficient inertia as by means of a weight attached thereto, or is otherwise rendered sluggish, as by means of springs to prevent its vibration into

engagement with the contacts 52 and 53 during this normal vibration of the member 39, with the result that the coils 31 and 32 of the magnetic clutch remain deenergized during this period.

- 5 To control the operation of the vibratory arm 39 in accordance with variations in the antenna impedance a pair of electron discharge devices 47 and 50, each comprising the usual anode, cathode and grid are employed. The anodes or plate member of the two discharge devices are connected to the secondary windings 10 and 11 in such a way that the electromotive forces supplied to the two anodes will be in phase with each other. The plate circuit of each discharge device is completed through one of the windings 46 or 49. The grid elements of the discharge devices are connected to one of the armature windings 20 of the inductor alternator 1. A resistor 56 and condensers 57 and 58 are connected in circuit with the armature winding of the alternator so that the phase relation of the electromotive forces supplied to the two grids 25 may be adjusted relatively to one another and relatively to the plate electromotive force as desired. Normally with the antenna in tune with the electromotive force of the alternator 1, the electromotive force supplied to the plate member of each discharge device 47 and 50 many differ in phase from the electromotive force supplied to the associated grid member by an amount less than 90 degrees and the difference in phase between the grid and plate electromotive forces of the two discharge devices may be equal. As thus arranged if the antenna is in tune with the high frequency electromotive force of the alternator 1 equal amounts of current 40 will be supplied from the discharge devices 47 and 50 to coils 46 and 49. Energization of coils 46 and 49, however, will not affect the operation of the vibratory member 39 as long as the coils 46 and 49 are supplied with current for equal periods of time. When the impedance of the antenna varies from normal, the phase relation of the electromotive forces supplied to the grids and plates of the discharge devices will vary, and as a result 45 the current supplied in any one cycle from one discharge device will flow for a longer period of time than from the other discharge device. This will cause one of the relay coils 46 or 49, as the case may be, to be supplied with current impulses of longer duration than those supplied to the other relay and as a result vibratory arm 39 will lag for a longer time at the pole piece 40 or 41 which is supplied with a greater amount of current.
- 50 If the capacitance of the antenna is, for example, decreased below normal coil 49 will be energized for a longer period and at a higher value than coil 46. Member 39 will, therefore, lag longer at pole piece 41 than at 40. Thus the relay 37 will be energized with

currents of one polarity for longer periods than with the other polarity. This causes the armature of the relay 37 to engage its contact 52, thereby energizing the coil 31 which in turn attracts the disk 27 into frictional engagement with the disk 23 and causes the shaft 21 to rotate in a direction to correct the antenna impedance. Likewise if the capacitance of the antenna is increased above normal then the vibratory member 39 will lag against pole piece 40 and the armature of the relay 37 will be moved into engagement with the contacts 53. The coil 32 of the magnetic clutch 22 will then be energized thereby moving the disk 28 into frictional engagement with the disk 24 and causing the shaft 21 to rotate in the opposite direction, thereby correcting the impedance of the antenna.

It will thus be seen that by the insertion of the relay 37 having an armature of comparatively large inertia between the magnetic clutch 22 and the relay 36, the magnetic clutch is rendered unresponsive to normal action of the vibratory member 39 but responsive to that member only as its action is modified by impedance variations in the antenna. In cases where the transmitted signals are effected by means of detuning the antenna responsively to operation of the transmitter, means are provided in accordance with my invention to prevent response of the magnetic clutch to this detuning effect. This means comprises the relay 38 having its contacts connected in circuit with the actuating coil of the relay 37 and the vibratory member 39. The actuating coil of the relay 38 is connected in circuit with the transmitting key 20 and with the source of potential 35. Thus when the key 20 is moved to the right as during periods when high frequency waves are being radiated by the antenna the actuating coil of the relay 38 will be energized and the clutch mechanism will respond to the action of the member 39. When the transmitting key 20 is moved to the left the contacts of the relay 38 open and the magnetic clutching device 22 will no longer respond.

In Fig. 2 I have shown a further illustration of a magnetic clutch which is employed in connection with my invention. In this Fig. 60 represents a shaft which is adapted to be driven at a constant speed by means of a motor 25 and 61 is a balance wheel of large inertia which is employed for the purpose of maintaining a constant speed. The sleeves 29 and 30 are each shown loosely mounted upon the shaft 21 and having connected therewith mitre gears 62 and 63. These gears are shown in mesh with the mitre gear 64 which is mounted upon the shaft 60. By this arrangement the sleeve 29 and 30 are driven at a constant speed in opposite directions, whereas normally the shaft 21 does not rotate. The disks 27 and 28 are mounted upon the shaft 21 and are adapted for slight lateral

movement with respect thereto. The coils 31 and 32 which are suitably enclosed in insulating material together with the cooperating disks are all enclosed in a suitable housing 65, the coils being suspended out of contact with the rotating members and circumferentially about sleeves 29 and 30.

I have found that with an arrangement of this kind wherein all of the parts having substantial inertia, including the rotor of the motor, are maintained in continuous rotation, very rapid positive action may be had. This is particularly desirable during stormy weather conditions when the capacitance of the antenna is subject to very rapid variations. However, in transmitting stations where the antenna is not subjected to rapid capacitance changes the magnetic clutch 22 may be replaced by the device which is shown in Fig. 3. In this figure it will be seen that the shaft 21 of the variometer 7 is driven directly by the armature of the motor 25. During normal conditions the armature of this motor does not revolve but is short circuited through a circuit including conductor 33, normally closed contacts of relay 31, armature of the motor 25 and normally closed contacts of relay 32. The actuating coils of the relays 31 and 32 correspond to the actuating coils 31 and 32 of the magnetic clutch shown in Fig. 1, and are similarly controlled from the relay 37 of Fig. 1. The energizing circuit conductors 33, 34 and 55 and contacts 52 and 53 for purposes of clearness, are similarly numbered in both figures. If, due to a change in antenna impedance, the armature of the relay 37 engages the contacts 52, relay 31 will be energized, thereby opening its normally closed contacts and closing its normally open contacts. A circuit will then be completed leading from the negative side of the source of potential 35, of Fig. 1, through conductor 34, lower contacts of the relay 31, field winding 66 of the motor 25, back through conductor 33 to the positive side of the source of potential 35, and likewise a circuit will be completed from conductor 34 through the upper contacts of the relay 31, armature of the motor 25, normally closed contacts of the relay 32 back through the conductor 33 to the positive side of the source of potential 35. The motor will then be energized in a manner to rotate the variometer shaft 21 in a direction to overcome the antenna impedance. When the antenna impedance has been corrected the armature of the relay 37 will interrupt the circuit of the relay 31. This relay will then return to its normal position, thereby short circuiting the armature of the motor 25 and causing the motor to stop. If the relay 37 engages its contact 53 then the relay 32 will be energized which opens its normally closed contacts and closes a circuit leading from the negative side of the source of potential 35 through conductor 34, lower contacts

of the relay 32, field winding 66 and conductor 33 back to the opposite side of the source of potential 35. Likewise a circuit is closed leading from the negative side of the source of potential 35 through the conductor 34, upper contact of the relay 32, armature of the motor 25, normally closed contacts of the relay 31 back through conductor 33 to the positive side of the source of potential 35. The motor will then be energized for rotation in the opposite direction to correct the antenna impedance.

While I have shown and described a particular embodiment of my invention it will, of course, be understood that I do not wish to be limited thereto since many modifications, both in the circuit arrangement and in the instrumentalities employed, may be made without departing from the spirit and scope of my invention as set forth in the appended claims.

What I claim as new and desire to secure by Letters Patent of the United States is:—

1. In combination, an antenna, regulating means and detuning means therefor, means for controlling said regulating means responsive to impedance variations in said antenna, and means for rendering said regulating means unresponsive to operation of said detuning means.

2. In combination, an antenna, regulating means therefor having a rotatable element, a vibratory member, means independent of the antenna impedance for producing normal vibratory action of said member, means for modifying the action of said vibratory member in accordance with impedance variations in said antenna and means for rotating said element in either direction dependent on the modified action of said vibratory member.

3. In combination, an antenna, regulating means therefor, a vibratory member, means independent of the antenna impedance for producing normal vibratory action of said member, means for modifying the action of said vibratory member in accordance with impedance variations in said antenna, means responsive to the modified action of said vibratory member and means for controlling said regulating means dependent upon the action of said last mentioned means.

4. In combination, an antenna regulating means therefor, detuning means for said antenna, a vibratory member, means for modifying the action of said vibratory member in accordance with impedance changes in said antenna, means for controlling said regulating means dependent upon the modified action of said vibratory member and means for rendering said last means unresponsive to operation of said detuning means.

5. In combination, an antenna, regulating means therefor including a rotatable element, a driving means and clutching means having oppositely rotating members normally actu-

ated by said driving means, said clutching means being connected to operate responsively to impedance changes in said antenna to connect said rotatable element to one of 5 said oppositely rotating members for rotation in either direction.

6. In combination, an antenna, regulating means therefor including a movable element, a driving means, means for detuning 10 said antenna, clutching means connected to operate responsively to impedance changes in said antenna to connect said movable element to said driving means and means for rendering said clutching means unresponsive to impedance variations produced by said detuning 15 means.

7. In combination, an antenna, regulating means therefor including a movable element, clutching means for operating said movable 20 element, a vibratory member, means independent of said antenna impedance for producing normal vibratory action of said member, means for modifying the action of said vibratory member in accordance with impedance 25 variations in said antenna, and means responsive to the modified action of said member for controlling said clutching means.

8. In combination, an antenna, regulating means therefor including a movable element, 30 clutching means for operating said movable element, means for detuning said antenna, a vibratory member, means for modifying the action of said vibratory member in accordance with impedance changes in said antenna. 35 means responsive to the modified action of said vibratory member to control said clutching means, and means whereby said responsive means is unaffected by operation of said detuning means.

40 9. In combination, an antenna, regulating means therefor including a rotatable element, a driving means, clutching means for connecting said element to said driving means for operation in either direction, means for detuning 45 said antenna, means responsive to impedance variations in said antenna for controlling said clutching means and means for rendering said impedance responsive means inoperative during operation of said detuning 50 means.

10. In combination, an antenna regulating means therefor, detuning means for said antenna, clutching means adapted to respond to impedance changes in said antenna to control 55 said regulating means and means for rendering said clutching means unresponsive to impedance variations in said antenna resulting from said detuning means.

11. In combination, an antenna, regulating 60 means therefor including a rotatable element, a continuously rotating driving means, clutching means for connecting said rotatable element to said driving means for rotation in either direction, a vibratory member, means 65 independent of said antenna impedance for

producing normal vibratory action of said member, means for modifying the action of said vibratory member in accordance with impedance variations in said antenna and means responsive to the modified action of 70 said member for controlling said clutching means.

12. In combination, an antenna, regulating means therefor, a vibratory member, means independent of said antenna impedance for producing normal vibratory action of said member, means for modifying the action of said vibratory member in accordance with impedance variations in said antenna and clutching means responsive to the modified 75 action of said member to control said regulating means.

In witness whereof, I have hereunto set my hand this 11th day of August, 1927.
